DESIGN FOR A DISPLAY CABINET FOR KNITTING NEEDLES, CROCHET HOOKS, OR THE LIKE

Ernest W. Slingsby, Deep River, Conn., assignor
to C. J. Bates & Son, Chester, Conn., a firm
composed of Hamilton C. Bates, Wells C. Bates,
and Hamilton C. Bates, Jr.

Application March 17, 1942, Serial No. 106,216

Term of patent 7 years

To all whom it may concern:

Be it known that I, Ernest W. Slingsby, a citizen of the United States, residing at Deep River, in the county of Middlesex and State of Connecticut, have invented a new, original, and ornamental Design for a Display Cabinet for Knitting Needles, Crochet Hooks, or the Like, of which the following is a specification, reference being had to the accompanying drawing, forming part thereof.

Fig. 1 is a front perspective view of a display cabinet for knitting needles, crochet hooks or the like, showing my new design; and

Fig. 2 is a rear perspective view of the display cabinet shown in Fig. 1.

I claim:

The ornamental design for a display cabinet for knitting needles, crochet hooks, or the like, as shown.

ERNEST W. SLINGSBY.
